[57] CLAIM

The ornamental design for a railroad hopper car cross ridge collar casting, as shown and described.

DESCRIPTION

FIG. 1 is a front elevational view of our new design of railroad hopper car cross ridge collar casting;
FIG. 2 is a rear elevational view thereof;
FIG. 3 is a side elevational view thereof, it being understood that the opposite side is a mirror image of that shown;

FIG. 4 is a sectional view thereof along the line 4—4 of FIG. 1;

FIG. 5 is a top plan view thereof; and

FIG. 6 is a bottom plan view thereof.

FIG. 1**FIG. 2****FIG. 3****FIG. 4****FIG. 5****FIG. 6**
